(57) **CLAIM**

The ornamental design for an holder for portable wireless communication device, as shown and described.

DESCRIPTION

FIG. 1 is a perspective view of the holder for portable wireless communication device

FIG. 2 is a front view of FIG. 1;

FIG. 3 is a back view of FIG. 1;

FIG. 4 is a top view of FIG. 1;

FIG. 5 is a bottom view of FIG. 1;

FIG. 6 is a right side view of FIG. 1; and,

FIG. 7 is a left side view of FIG. 1.

(Continued)

The broken lines in the drawings are for the purpose of illustrating portions of the holder for portable wireless communication device that form no part of the claimed design.

1 Claim, 7 Drawing Sheets
